UNITED STATES PATENT OFFICE.

EDWARD F. McINTYRE, OF ST. PAUL, MINNESOTA, ASSIGNOR OF ONE-HALF TO OSCAR ROSLUND, OF ST. PAUL; MINNESOTA.

OAR-LOCK.

SPECIFICATION forming part of Letters Patent No. 758,270, dated April 26, 1904.

Application filed May 7, 1903. Serial No. 156,011. (No model.)

To all whom it may concern:

Be it known that I, EDWARD F. McINTYRE, a citizen of the United States, residing at St. Paul, in the county of Ramsey and State of Minnesota, have invented certain new and useful Improvements in Oar-Locks; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in oar-locks; and the object of the invention is to provide a cheap, simple, but efficient oar-lock of the class which cannot be accidentally removed from the boat, but may be easily detached therefrom, and which when on the boat will not be apt to get its mechanism obstructed by snow, ice, or dirt.

In the accompanying drawings, Figure 1 is a top view of a portion of a gunwale of a boat with the frame of my device secured thereon. Fig. 2 is an inside elevation of the gunwale with my improved oar-lock secured thereon. Fig. 3 is a transverse vertical section about as on the line *a a* in Fig. 2.

Referring to the drawings by reference-numbers, 4 designates the gunwale of the boat. Upon it is secured by screws 5 the angular plate 6, which may be termed the "frame" or "seat" of the oar-lock. Near the middle of the frame is formed a vertical socket 7, in which the round shank 8 of the fork or oar-lock proper, 9, is dropped. Said shank is provided with an annular recess 10, in which engages the tooth 11, secured in a flat spring-arm 12, which has its upper end secured at 13 in a vertical recess 14, formed in the outer side of the frame next to the gunwale, so that the spring-arm plays between the gunwale and the casting and has always a tension toward the groove 10 of the shank, so that when the latter is to be removed the operator must press on the lower end of the spring away from the shank, and as the shank is inserted in the socket

the slant of the point of the tooth 11 or the cone shape of the end of the shank, or both, force the spring toward the gunwale until the 50 recess 10 can receive the tooth, when the spring comes back to its normal position, and thus locks the shank in place against accidental removal.

Among the advantages of the device as compared to any earlier devices in its line is the inverted form of the recess or pocket 14, in which the spring-arm is situated so that no dirt, ice, or snow can accumulate in it and obstruct the action of the spring. It is also 55 very cheap and simple to make, in that the rivet or stud 13 may be made of malleable iron integral with the plate 6. The spring itself may be stamped or cut from band-steel from which the catch 11 may be formed integrally. The finger-catch formed of the free end of the spring is also in a place so out of the way that it cannot easily get broken or interfered with.

Having thus described my invention, what 70 I claim, and desire to secure by Letters Patent, is—

In an oar-lock, the combination with a frame or plate securable to the gunwale of a boat and having a socket extending downward at 75 the inner side of the gunwale and provided with a vertical recess upon the side nearest the gunwale, an aperture from the recess into the socket, a spring-arm secured with one end in the upper part of the recess and having its 80 free end projecting below the socket, to form a finger-catch, a tooth formed upon the spring-arm and projecting through the aperture into the socket, a fork having a cylindrical shank adapted to be inserted in the socket and having 85 an annular groove for the tooth of the spring-arm to engage.

In testimony whereof I affix my signature in presence of two witnesses.

EDWARD F. McINTYRE.
